UNITED STATES PATENT OFFICE.

WILLIAM H. PAGE AND GEORGE C. SETCHELL, OF NORWICH, CONNECTICUT,
ASSIGNORS TO THE WILLIAM H. PAGE WOOD TYPE COMPANY, OF SAME
PLACE.

DIE FOR FORMING WOOD TYPE.

SPECIFICATION forming part of Letters Patent No. 402,850, dated May 7, 1889.

Application filed December 5, 1888. Serial No. 292,719. (No model.)

To all whom it may concern:

Be it known that we, WILLIAM H. PAGE and GEORGE C. SETCHELL, of Norwich, in the county of New London and State of Connecticut, have invented a new and useful Improvement in Dies for Forming Wood Type; and we do hereby declare that the following is a full, clear, and exact description of the same.

10 Our said invention relates to dies for forming wood type by compression. It is shown in connection with the sectional dies fully described in an application filed in the United States Patent Office on the 5th day of December, 1888, Serial No. 292,734, by William H. Page, one of the joint inventors of this invention; but the said invention is not limited to use or combination with dies made in section strictly, but may be used with dies made with 15 open sides where the dies represent substantially the whole letter or figure.

The invention is designed to secure the more accurate and expeditious manufacture of the wooden type.

20 It consists, essentially, of an interposed strip combined with the dies representing the characters adapted to form sunken spaces between the characters on the blocks of the type when such characters are arranged in groups in the blocks, or to form a shoulder on the type, or to leave the outside of the type with a finished side when the die by which it is made has an open side.

We have illustrated our invention in the 25 accompanying drawings, in which—

Figure 1 represents in plan the die required to make the type for the letter X. Fig. 2 represents the same with the sections separated. Fig. 3 shows in plan a die for the letter M, and Fig. 4 represents the same with the parts separated. Fig. 5 shows one die in side elevation. Fig. 6 shows in plan a group of type on one block as formed by a group of dies. Fig. 7 shows the same in end view.

40 In Figs. 1 and 2 the part of the die marked A represents the body of the letter X, this being used as a sample or representation letter to illustrate the principle of the invention. The raised parts of the die, which correspond

with the depressed portions of the type, are marked a, and the sunken parts of the die are indicated by the surface having the hatchings. The parts thus marked are all on the one piece A, and form all the body of the letter. The division between the legs or 55 branches of the letter is formed by the narrow ribs a' a', with the enlarged terminals, and the rest of the block or section is occupied by the raised portions a a. The parts between the ends of these raised portions and 60 the ends of the block are open at the sides, and if this block were used alone the side of the type would need to be formed after the impression, whether the type were formed separately or in groups on a single block. 65 The side of the type would be determined by the side of the block, and not by the line xx, which is the correct line or margin of the letter. Further, if the type were formed in groups on a single block the parts of the letter would be continuous with the spaces left 70 between the letters. For example, the raised part a of the letter X would be continuous with the surface of the block between this letter and the next on the same block. To 75 form this margin and to give shape to the letter, we provide the intermediate pieces, b, straight and plain pieces, as wide or a little wider than the space required between the type when they are formed on the same block 80 and as deep as the other parts of the dies. These being separate and removable, the part A is open, and the interior grooves are accessible to the file for finishing the interior faces and angles left imperfect by the engraving- 85 tool.

The strips b may be used for the purpose of leaving the die-pieces open on the sides for facility of finishing, as wide exactly as the saw-kerf which divides the block; but it is 90 desirable to leave a shoulder, c, on the side of the type which equals one-half the space between the type when set, and thus forms half the spacing-block or spaces. The shoulders c on each side equal the whole width of 95 the strip b less the saw-kerf.

In Figs. 3 and 4 we have shown a die for the letter M, in which the letter-die is com-

posed of three pieces, the central piece, D, being special to the letter, and the side pieces, d d, being interchangeable. These pieces d d have open sides also, as shown at a^2 , and 5 these are bounded by the strips b, as in the previous figures, and with the effect heretofore described. The sections and interposed strips are formed with beveled notches in the ends, which register when all the pieces are 10 in the same plane, and which receive corresponding ribs on the clamp.

We claim as our invention—

1. A die for forming type by impression, having parts of its sides raised and parts depressed and open, substantially as described. 15
2. A die for forming type by impression, having parts of its sides raised and parts depressed and open, in combination with the strip b, adapted to close the open side.

3. Combined with the die having parts of 20 its sides raised and parts depressed, the strip b, for closing the open side, of a width greater than the required distance between the type, substantially as described.

4. A die for forming type by impression, 25 formed in sections and with portions of the depressed surface of the outer sections extending to the sides, combined with the strip b, for closing the open side, substantially as described. 30

In testimony whereof we have signed our names to this specification in the presence of two subscribing witnesses.

WILLIAM H. PAGE.
GEORGE C. SETCHELL.
